LIGHTING ATTACHMENT FOR SEWING MACHINES

Filed May 8, 1924

Patented May 26, 1925.

1,538,927

UNITED STATES PATENT OFFICE.

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY.

LIGHTING ATTACHMENT FOR SEWING MACHINES.

Application filed May 8, 1924. Serial No. 711,812.

To all whom it may concern:

Be it known that I, DANIEL H. CHASON, a citizen of the United States, residing at Elizabeth, in the county of Union and State 5 of New Jersey, have invented certain new and useful Improvements in Lighting Attachments for Sewing Machines, of which the following is a specification, reference being had therein to the accompanying drawings.

Sewing machines are commonly made with an opening at the rear side of the hollow bracket-arm or gooseneck, adjacent the bend of the latter, to afford access to the 15 mechanism therewithin for assembling, adjusting, inspection and oiling purposes. When the machine leaves the factory, this opening is closed by means of a thin sheet-metal cover-plate, known as the arm-side 20 cover-plate, which is embossed and nickel-plated to give it an ornamental and pleasing appearance. This cover-plate is secured to the arm by means of a single thumb-screw, which passes through a small hole 25 near the top of the plate and is threaded into the arm above the arm-side opening. By loosening this thumb-screw the cover-plate may be swung around such screw as a pivot to expose the arm-side opening and 30 afford access to the mechanism in the arm.

The owner of such a machine desirous of equipping it with a lighting attachment has usually adopted the type disclosed in the patent to Diehl No. 1,488,233, of March 25, 35 1924, and comprising an electric lamp-socket, lamp and reflector, mounted on a substitute cover-plate adapted to replace the original cover-plate. Such substitute cover-plate is formed with a lamp-carrying ear 40 extending rearwardly at right angles to the plane of the plate proper, and with a steady-ing lug coacting with the sewing machine frame to prevent sagging of the lamp. Such plate is made of heavy and correspondingly expensive stock in order that it 45 may possess the strength and rigidity necessary to support the lamp. When the lighting attachment with its substitute cover-plate is applied to the machine, the original cover-plate is discarded.

With such an attachment in place, the user must disturb the lamp by swinging the substitute cover-plate lamp, reflector and all, around the thumb-screw, in order 55 to gain access to the mechanism within the

arm. Furthermore, the thumb-screw must be loosened several turns to permit the steady-ing lug on the cover-plate to pass the rim of the opening.

According to the present improvement, 60 the lamp is carried by a skeleton cover-plate which is not to be substituted for the usual thin metal cover-plate with which the machine is originally equipped, but is to be interposed between such original cover-plate and the machine frame, so that the aperture in the skeleton plate registers with the aperture in the machine frame; both plates being secured in position by the usual cover-plate thumb-screw at the top side of 65 the aperture. Thus, the original cover-plate may be swung about the thumb-screw to expose the aperture in the machine frame without disturbing the skeleton plate and lamp carried thereby. Further, the use of 70 a skeleton lamp-support enables a considerable saving in metal to be effected. The skeleton plate of the present sewing machine lighting attachment need not be specially ornamented or highly finished, as it 75 is adapted to be covered and substantially concealed by the ornamental arm-side cover-plate with which the machine was originally equipped.

In the accompanying drawings, Fig. 1 is 80 a rear side elevation of a sewing machine and lighting attachment embodying the invention. Fig. 2 is a section on the line 2—2, Fig. 1, Fig. 3 is a fragmentary top plan view of the lighting attachment as applied to the machine and Fig. 4 is a perspective view of the lighting attachment.

The sewing machine comprises the usual frame, including the bed 1, and gooseneck 95 or bracket-arm 2 terminating in the head 3 and formed at its rear side adjacent its bend with an aperture 4 which is originally covered by the usual thin-metal arm-side cover-plate 5; the latter being commonly embossed and nickel-plated to give it and the machine an ornamental and pleasing appearance. The original cover-plate 5 is secured in position over the frame aperture 4 by means of the thumb-screw 6 which may be readily loosened to permit the plate 5 100 to be swung to dotted line position, Fig. 1, to expose the aperture 4 for access to the mechanism within the arm 2.

According to the present improvement, a 110 lamp-socket 7, lamp 8 and reflector 9, such

as disclosed in the Diehl patent referred to, are secured to the lateral ear 10 formed on the skeleton cover-plate 11 which is preferably of circular form and has an aperture 12 of substantially the shape and size of the sewing machine frame aperture 4. The plate 11 is also provided with a thumb-screw aperture 13 above the aperture 12, and has the integral steadyng lugs 14 at 10 opposite sides of the aperture 13. The lugs 14 coact with the rim of the frame aperture 4 to prevent sagging or upward displacement of the lamp-socket when in use or when the thumb-screw 6 is loosened to the 15 original cover-plate 5 to be shifted to dotted line or open position.

The lamp-socket 7 is preferably secured yieldingly to the ear 10 by means of a headed nipple 15 having a notched flange 16 20 and a reduced threaded portion 17 passing through the aperture 18 in the ear 10, bushed by means of a felt washer 19 and entering the socket 7. Felt face washers 20 and 21 are provided between the opposite faces of 25 the ear 10 and the flange 16 and metal washer 22, respectively. A pin 23 fixed to the ear 10 enters a notch in the flange 16 to prevent rotary displacement of the socket 7.

Having thus set forth the nature of the 30 invention, what I claim herein is:—

1. The combination with a sewing machine frame having the usual apertured hol-

low arm and arm-side cover-plate, of an apertured plate interposed between said arm and arm-side cover-plate, and an electric lamp-socket carried by said apertured plate.

2. A lighting attachment for sewing machines comprising a skeleton cover-plate having an aperture adapted to expose the usual aperture at the rear side of a sewing machine bracket-arm, and also having a thumb-screw aperture above said first mentioned aperture, and an electric lamp-socket carried by said skeleton plate, said skeleton plate being adapted to be interposed between the sewing machine frame and the usual arm-side cover-plate and supported by the usual cover-plate thumb-screw.

3. The combination with a sewing machine frame having the usual side apertured hollow arm, arm-side cover-plate, and cover-plate thumb-screw, of an apertured plate interposed between said arm and arm-side cover-plate and held in position by said thumb-screw, and an electric lamp-socket 55 carried by said apertured plate, said apertured plate having means coacting with the sewing machine frame to prevent sagging of the lamp-socket from working position when said thumb-screw is loosened.

In testimony whereof, I have signed my name to this specification.

DANIEL H. CHASON.
